CLAIM

The ornamental design for a tire, as shown and described.

DESCRIPTION

FIG. 1 is a front elevational view of a tire showing our new design, a rear elevational view, a top plan view and a bottom plan view being identical to the front elevational view; FIG. 2 is a left side view thereof, a right side view being a mirror image thereof;

FIG. 3 is a right side perspective view thereof;

FIG. 4 is a left side perspective view thereof;

FIG. 5 is an enlarged view of the selected portion in FIG. 1;

FIG. 6 is an enlarged view of the selected portion in FIG. 2;

FIG. 7 is an enlarged view of the selected portion in FIG. 3; and,

FIG. 8 is an enlarged view of the selected portion in FIG. 4. The dash-dash broken lines in the drawings depict the portions of the tire that form no part of the claimed design. The dot-dash broken lines in the drawings depict the boundaries of the enlarged views and form no part of the claimed design.
